UNITED STATES PATENT OFFICE.

FRED N. LIVINGSTON, OF SEATTLE, WASHINGTON.

FUEL MIXER.

1,406,398.

Specification of Letters Patent. Patented Feb. 14, 1922.

Application filed July 2, 1919. Serial No. 308,128.

To all whom it may concern:

Be it known that I, FRED N. LIVINGSTON, a citizen of the United States, residing at 1534 W. 58 St., Seattle, in the county of 5 King and State of Washington, have invented certain new and useful Improvements in Fuel Mixers; and I do hereby declare the following to be full, clear, and exact description of the invention, such as will enable 10 others skilled in the art to which it appertains to make and use the same.

This invention relates to screens for breaking up particles of gasoline or fuel oil for the purpose of better mixing the same with 15 air for burning, particularly for internal combustion engines

Great importance in operating gasoline engines rests in the proper mixture of air and fine particles of gasoline or gaseous fuel, 20 as the power of the engine on a given amount of gasoline or gas depends largely on the amount of air that is mixed before the fuel is fired, and in order to secure the best mixture it is necessary that the particles of oil be 25 broken into the smallest parts possible and it is the object of my invention to produce a simple and effective apparatus that may be readily affixed between the ordinary carburetor and the intake pipe of the engine 30 and which will cause the oil or fuel to be broken up as desired and properly mixed with air.

Figure 1 is a top plan of my device, and

Figure 2 is a side view of the same.

35 My device consists of a sheet 1, of metal constructed in size and form of an ordinary metal gasket to be held between the joints of the carburetor and intake pipe by means of the ordinary coupling bolts, passed 40 through the holes 2 provided near the ends of the plate.

The central portion of the sheet is provided with a shallow circular boss or embossment 3 which fits into the intake pipe in 45 ordinary use, and six (or more or less according to the size of device) slots are formed in the embossment, the slots of greater width at the top than at the base of the embossment, where they may terminate in a V 50 point.

The cutting out of these slots necessarily leaves wedge shaped sections or leaves 6 of the body 3 between the slots, and in these remaining wedge sections I bore two or more holes 5, the hole in the wider part of the 55 leaf being larger than the other, and these holes I make before the cone is pressed, preferably so that the walls of the holes are at right angles with the face of the body portion of the device, and then when the body 3 60 is pressed into position, these holes and their walls will all diverge in line from the walls of the cone.

In use, the device is placed in the proper position in the fuel intake pipe, so that the 65 gasoline or oil must pass through the slots and holes, and in so passing the diverging walls of the holes and arrangement of the slots will cause the gasoline or oil to be sprayed in diverging and cross lines and 70 broken up into a finely gaseous mixture with air then supplied. The device is placed between the carburetor and the intake manifold, with the top or convergent body toward the engine and away from the carburetor. 75

Having described my invention, I claim—

1. A mixing device comprising a plate adapted to be clamped between sections of a fuel-intake for gasoline engines, said plate 80 having a hollow boss projecting from its central portion, and said boss having radiating slots in its wall and holes between the slots.

2. A mixing device comprising a plate 85 adapted to be clamped between sections of a fuel-intake for gasoline engines, said plate having a hollow boss projecting from its central portion, said boss having radiating slots in its walls decreasing in width toward 90 their outer ends, and a plurality of holes of different sizes between the slots so disposed that holes farthest from the center are larger than holes nearer the center, the axis of the holes being normal to the local surface. 95

In testimony whereof I affix my signature.

FRED N. LIVINGSTON.
